UNITED STATES PATENT OFFICE.

CLAUDE M. GARLAND, OF COLLINGSWOOD, NEW JERSEY, ASSIGNOR TO CAMDEN IRON WORKS, OF CAMDEN, NEW JERSEY, A CORPORATION OF NEW JERSEY.

GAS PRODUCER.

1,079,234.

Specification of Letters Patent.

Patented Nov. 18, 1913.

Application filed January 6, 1913. Serial No. 740,469.

To all whom it may concern:

Be it known that I, CLAUDE M. GARLAND, a citizen of the United States, residing in Collingswood, county of Camden, State of New Jersey, have invented certain Improvements in Gas-Producers, of which the following is a specification.

One object of my invention is to provide means for supporting the slicer bars independently of the casing of the gas producer.

A further object of the invention is to support the said bars so that they will withstand the strains to which they are subjected.

15 In the accompanying drawings:—Figure 1, is a sectional elevation illustrating my gas producer; Fig. 2, is a plan view, and Fig. 3, is an end view looking in the direction of the arrow, Fig. 1, of the upper part 20 of the producer.

Referring to the drawings, 1 is the base on which the gas producer is mounted.

2 is rotating body portion of the producer.

25 3 is an air pipe extending into the cone 4.

The producer is sealed, in the ordinary manner, as shown.

5 5 is an annular rack on the base section and meshing with this rack is a pinion 6 30 on the driving shaft 7 by which the lower body portion of the producer is rotated. This body portion rests on a series of flanged wheels 8 pivoted to bearings, as shown in Fig. 1.

35 9 illustrates the fixed framework of the producer and 10 is the top section which is supported by said framework. This section is stepped, as illustrated, the portion 11 being less in height than the portion 12 40 and in this portion 12 is the fuel opening 13 and the gas outlet 14. The joint between the rotating body portion 2 and the top section 10 is sealed, in the present instance, by a water seal.

5 15 is a heavy beam extending from one side of the producer to the other and resting on the fixed framework 9, as clearly shown in Fig. 3. This beam extends over the portion 11 of the top section 10, preferably close to the raised portion and carries three slicer bars 16, in the present instance, one preferably arranged midway between the ends; another one near the center, and the third near one end. As the beam is at

one side of the center of the producer, the 55 slicer bars cut individual paths in the coking coal as the body portion of the producer is rotated. By mounting the bars on the beam, as shown, and supporting the beam independently of the producer, the producer 60 is entirely relieved from strains; the strains being taken by the beam and the supporting framework. These parts can be made of sufficient strength to resist the pressure to which the slicer bars are subjected. The 65 outer casing of each slicer bar is firmly mounted in the beam 15 and passes through an opening 18 in the top section 10; the openings being closed by a packing ring, or other suitable means, as illustrated in the 70 drawings. Extending upwardly from the slicer bars is a screw stem 19 adapted to a bearing 20 securely mounted on the beam 15 and on the end of this screw stem is a handled nut 21. Under the bearing is a jam 75 nut 22. By this construction each slicer bar can be raised or lowered, as desired.

23 is a pipe extending through the screw stem 19 and slicer bar 16 to a point near the lower end of the slicer bars.

24 is an outlet pipe projecting from the slicer bars above the beam.

Water is introduced through the pipe 23 and circulates through the slicer bars and out through the pipe 24 in order to keep the 85 slicer bars cool.

By the above construction, it will be seen that I make a very substantial support for the slicer bars and as they are entirely independent of the top section of the producer, 90 the producer can be made of much lighter material than where the bars are carried by the said top section. This arrangement also simplifies the construction of a producer of this type.

95 I claim:

1. The combination in a gas producer, of a rotating body portion; a fixed top section; a supporting frame; a beam extending directly over the fixed top section and at one 100 side of the center thereof and resting on the supporting frame; a bearing for the slicer bar secured to the beam; and a slicer bar mounted in the bearing and extending through the top section into the body of the 105 producer, the beam being the sole support of the slicer bar.
2. The combination in a gas producer, of

2

5 a rotating body portion; a fixed top section; a supporting frame; a beam having its ends resting on the supporting frame and extending over the top section; a series of slicer bars carried by the beam and extending through the top section into the body of the producer; said slicer bars being spaced different distances apart so that as the body portion of the producer rotates, the bars will

10 cut through the coking coal in different paths.

15 3. The combination in a gas producer, of a body portion; a top section; a supporting frame; a beam having its ends resting on the frame and extending over and clear of the top section; slicer bars mounted in the frame and extending through openings in the top section and into the body of the producer; bearings mounted on the beam; each

20 20 slicer bar having a threaded extension projecting through the bearings; and a nut on

each threaded extension for vertically adjusting the slicer bars.

4. The combination in a gas producer, of a rotating body portion; a stepped upper portion; a feed hopper mounted in the elevated section of the upper portion; said section also having a gas outlet; a supporting framework; a beam having its ends resting on the framework and extending over the lower section of the top portion of the gas producer; with a slicer bar mounted on the beam and extending through the top section and into the body of the producer.

25 30 35 In testimony whereof, I have signed my name to this specification, in the presence of two subscribing witnesses.

CLAUDE M. GARLAND.
